CLAIM

The ornamental design for a beverage container insulator, as shown and described.

DESCRIPTION

FIG. 1 is a front elevation of a beverage container insulator of a first embodiment of the present design, the rear, left side, and right side elevations being identical thereto; FIG. 2 is a top plan of the beverage container insulator of the first embodiment;

FIG. 3 is a bottom plan of the beverage container insulator of the first embodiment;

FIG. 4 is an elevational cross section of the beverage container insulator of the first embodiment taken in the plain of line 4-4 of FIG. 2;

FIG. 5 is a front elevation of a beverage container insulator of a second embodiment of the present design, the rear, left side, and right side elevations of said second embodiment being identical thereto;

FIG. 6 is a top plan of the beverage container insulator of the second embodiment, said bottom plan of the beverage container insulator of the second embodiment being identical to FIG. 3; and,

FIG. 7 is an elevational cross section of the beverage container insulator of the second embodiment taken in the plain of line 7-7 of FIG. 6.

The dashed lines in the figures illustrate environmental features forming no part of the claimed design. The blind internal surfaces of the beverage container insulator of the first, second, and third embodiments forming no part of this design.
